LIQUID MIXER

Milton S. Dunkelberger, Dayton, Ohio

Application October 4, 1935, Serial No. 43,521

1 Claim. (Cl. 259—108)

This invention relates to new and useful improvements in liquid mixers.

It is one of the principal objects of my invention to provide for mixing liquids such as malted milk, medicines, paints and the like, a container having in its bottom a well in which an electric rotor carrying an agitator is readily insertible. This agitator and rotor unit is compact, economical and easily removable for the purpose of 10 cleaning and repair, and when in operation, will draw the liquid downwardly, and agitate it thoroughly, to completely mix the same. In respect to these advantages, as well as others to be hereinafter pointed out, my liquid mixer is 15 superior to the present type in which the motor and dependent agitator are mounted in the upper part of the container.

In the accompanying drawing illustrating my invention, Figure 1 is a vertical, sectional view taken through the liquid container, showing the agitator assembly in the bottom portion thereof. Figure 2 is a horizontal sectional view taken through the same on the line 2—2 of Figure 1. And Figure 3 is a top plan view of the agitator.

Referring to the accompanying drawing for a detailed description of my invention, the numeral 1 designates a conventional liquid container having a spout 2, handle 3, lid 4 and bottom 5. Crimped to the bottom 5 is a hollow base 6. Formed in the bottom 5 is a hole which receives a metal sleeve 7 that is outwardly flanged at its upper end to rest upon said bottom while projecting downwardly therefrom into the hollow base to form a well.

The sleeve 7 has a bottom 8 which is depressed at its central portion to receive a bearing 9 for the lower end of a removable, vertical agitator shaft 10. The upper part of the shaft 10 is rotatable in a bearing cap 11 that is externally flanged, for support upon the flanged top of the sleeve over a laminated rotor 12 carried by the middle portion of the shaft. This bearing cap 11 is formed with holes 13 through which liquid may flow from the container into the well formed by the sleeve to lubricate the bearing 9.

Attached to the upper end of the agitator shaft 10, in this instance between a collar 14 and a thumb nut 15, is a blade unit 16 comprising three upwardly pitched wing blades 17 that are joined to a central web 18. (See Figure 3.) Each

blade is formed with a plurality of holes 19, in this instance three of gradually diminishing size, to assist in thoroughly agitating the liquid in the container when the blade unit is rotated by the following described means.

Secured to the sleeve 7 is a conventional laminated stator 20. Provided in one end of the stator is a hole that receives the sleeve, to which this end of the stator is attached at a place where it will completely surround the rotor 12 to revolve the latter. At its other end the stator 20 carries the conventional stator winding 21 from which wires 22, 22 lead to prongs 23, 23 in a socket 24 that receives a plug 25 carrying wires 26 which conduct electric current to it from a source of alternating current not shown.

When alternating current flows to the winding 21, the rotor 10 carried by the shaft 10 will be rotated by the stator to revolve the blades 17 in the direction of the arrow in Figure 3. Whirling at a fast rate in the bottom portion of the container, these apertured blades will thoroughly and completely mix a liquid such as malted milk in the container, while some of it flows downwardly through the holes 13 in the bearing cap 11 to lubricate the bearing 9.

The shaft 10 carrying the rotor 12 and blade unit 16, together with the bearing cap 11, may be easily lifted from the sleeve 7 for cleaning and repair. My well construction not only makes this possible, but enables the blade assembly to be mounted in the lower portion of the container where it will operate more efficiently, since solid matter in the liquid to be mixed will be drawn by it and gravity to that portion of the container, where it will be thoroughly agitated by the blades.

Having described my invention, I claim:

In a container, a bottom having a well portion, said well being formed with a depression at its center, a bearing in said depression, an agitator shaft axially placed in said well, an agitator secured to the shaft above the well, said shaft being removably supported at its lower end by said bearing, an alternating current rotor carried by said agitator shaft in the well and being removable therewith from the top of the latter, and a stator surrounding the rotor to revolve the agitator shaft.

MILTON S. DUNKELBERGER. 50
